UNITED STATES PATENT OFFICE

WILLIAM MAYO VENABLE, OF PITTSBURGH, PENNSYLVANIA, ASSIGNOR TO BLAW-KNOX COMPANY, OF PITTSBURGH, PENNSYLVANIA, A CORPORATION OF NEW JERSEY

EXCAVATING BUCKET

Application filed April 22, 1930. Serial No. 446,223.

This invention relates to excavating buckets and is particularly applicable to that type of bucket known as the lever arm bucket with which type two cables are generally employed, one of which is the holding or lifting cable and the other one the operating cable.

The invention is especially adapted for use in connection with lever arm buckets in which the closing line, after passing around a sheave in the lever arm and a sheave in the bucket head, returns again to the lever arm, either to be fastened thereto, or to pass around another sheave in the lever arm and then return to the head. In buckets of this kind there is an upper or head block containing sheaves and a lower or lever arm block also containing sheaves, and if both of these blocks are rigidly secured to their respective supporting structures, the leads of the line may be made perfect for one position of the lever arm only, as, for example, when the bucket is fully closed or when it is fully open, or in some intermediate position, and the amount of the off-lead in other positions will depend upon various features of the design, such as the length of the lever arm, the position of the sheaves in the head, and, as will appear more clearly hereinafter, upon the position of the head pin.

With the foregoing in mind the principal object of my invention may be said to reside in the provision of a bucket of the character described in which the head pin is so located in relation to the head sheaves, the lever arm sheaves and the several hinges and pivots of the bucket as to make more nearly perfect the leads of the line than has been possible with constructions previously in use.

It is also an object of my invention to obtain a greater spread of the bucket when open in comparison with the bucket height, as well as to improve the performance of the bucket by distributing to better advantage the grappling effort caused by pulling on the closing line during a closing operation.

Incidentally, it is an object of the invention to simplify the construction of the lever arm and also to somewhat raise the main hinge pin so as to give the scoops a greater reach

without increasing the head room required for operation.

A still further object of the invention resides in the provision of a construction by means of which a greater closing force is made possible by virtue of the fact that more line is pulled during the closing operation than has been possible with lever arm buckets heretofore in use.

The accompanying drawings illustrate the invention in preferred form—Fig. 1 being a side elevation of the bucket in closed position; Fig. 2 an end view of Fig. 1, and Fig. 3 a side elevation of the bucket in its wide open position.

Referring to the drawings it will be seen that I have illustrated a bucket of the ordinary four-hinged type in which the two scoop members 4 and the two pairs of corner bars 5 and 6 are pivoted together so as to form a four hinged frame. The scoops are provided with the customary hinge castings 7 and 8 pivoted together by the main hinge pin 9, and at each outer upper corner of each scoop 4 is a corner bracket 10 to which the lower ends of the corner bars 5 and 6 are pivoted by means of the corner pins 11.

Mounted upon the main hinge pin 9 is the lever arm 12 which is formed integrally with the hub portion 13 and the hinge casting 7, the hub portion being mounted as shown upon the main hinge pin 9.

The bucket head 14 carries the head pin 15 which it will be noted is located to the right of the vertical center line of the bucket which passes through the main hinge pin 9.

The lever arm sheaves 16 turn upon the pin 17 which is parallel to the head pin 15, the main hinge pin 9 and the corner pins 11, which pins articulate the frame. The head sheaves 17' turn on the pin 18, which it will be seen is not made parallel with any of the other pins but is so tilted with respect to them as to make the line leads from the head sheaves 17' to the lever arm sheaves 16 as perfect as possible. Furthermore, it will be noted that I have placed the head sheaves directly above the lever arm sheaves when the bucket is in the closed position illustrated in Fig. 1, and that the head pin is not on the 100

center line as in previous constructions, but on the side thereof which is opposite to that of the lever arm sheaves. With this arrangement, as the bucket opens, the lever arm descends substantially vertically until it reaches the position shown in Fig. 3, and during the operation the head will tilt but very slightly owing to the greater or less spreading of the corner bars. In this way the leads of the operating cable 19 will remain much more nearly perfect than if the lever arm is skewed and the head sheaves are mounted on a head pin which is located on the center line of the bucket or than if the head pin is disposed directly over the lever arm with the head sheaves on the opposite side, an arrangement sometimes adopted in previous constructions.

The bucket is operated, of course, by pulling or releasing the cable 19 as is well understood by those skilled in the art, the main hinge pin 9 being lowered with respect to the head during an opening movement and raised during a closing movement.

It will be observed that with a construction of this kind the corner bars 5 and 6 attain their greatest spread at a point intermediate the fully closed and the fully opened positions of the bucket, this position occurring approximately at the moment when the corner pins 11 and the main hinge pin 9 are in substantially a straight line. Closing the bucket from this position involves a lowering of the head sheaves more rapidly than the head pin which, of course, results in a greater closing force being exerted because more line is pulled during the closing operation than would be the case were the sheaves on the head pin itself. This is of distinct advantage in the heavy work to which this type of bucket is best adapted.

I claim:

1. A lever arm bucket having a head pin and lever arm sheaves characterized by the fact that the pin and the sheaves are located on opposite sides of the vertical center line of the bucket.

2. A lever arm bucket having a head pin, head sheaves and lever arm sheaves characterized by the fact that the pin and the sheaves in the lever arm are located on opposite sides of the vertical center line of the bucket, and further by the fact that the head sheaves are substantially vertically above the lever arm sheaves.

3. A lever arm bucket having a head pin, head sheaves and lever arm sheaves characterized by the fact that the pin and the sheaves in the lever arm are located on opposite sides of the vertical center line of the bucket, and further by the fact that the head sheaves are substantially vertically above the lever arm sheaves and are canted with respect to the lever arm sheaves to correct the lead of the operating cable.

4. In a bucket, the combination of hinged

scoop members, a lever arm, a lever arm sheave, a bucket head, a head sheave to one side of the center line of the bucket and above the lever arm sheave, and a head pin on the opposite side of the center line.

5. In a bucket, the combination with the operating cable of a pair of scoops, a main hinge pin, corner bars, corner pins, a lever arm, a lever arm sheave, a bucket head, a head pin on the side of the center line of the bucket which is opposite to that of the lever arm sheave, said hinge pin, corner pins and head pin being parallel, and a head sheave above the lever arm sheave mounted with its axis at an angle with respect to said parallel pins whereby to correct the lead of the operating cable.

In testimony whereof, I have hereunto signed my name.

WILLIAM MAYO VENABLE.
